UNITED STATES PATENT OFFICE.

CHARLES F. KETTERING AND WILLIAM A. CHRYST, OF DAYTON, OHIO, ASSIGNEES
TO THE DAYTON ENGINEERING LABORATORIES COMPANY, A CORPORATION OF
OHIO.

ENGINE-STARTING SYSTEM.

1,391,194.

Specification of Letters Patent. Patented Sept. 20, 1921.

Original application filed May 25, 1915, Serial No. 30,399. Divided and this application filed October 31, 1917. Serial No. 199,411.

To all whom it may concern:

- Be it known that we, CHARLES F. KETTERING and WILLIAM A. CHRYST, citizens of the United States of America, residing at 5 city of Dayton, county of Montgomery, and State of Ohio, have invented certain new and useful Improvements in Engine-Starting Systems, of which the following is a full, clear, and exact description.
- 10 This invention relates to improvements in engine starting systems and more particularly to that type of starting systems which are to be applied to the driving motors of self-propelled vehicles.
- 15 The present application is a division of the co-pending application of Charles F. Kettering and William A. Chryst, Serial No. 30,399, filed May 25, 1915, and patented August 12, 1919, No. 1,312,549.
- 20 Among the objects of the present invention is to provide a starting system which includes an electric machine capable of acting as a motor for cranking purposes and as a generator for charging purposes.
- 25 It is another object of the present invention to provide a starting system, wherein the electric machine, when acting as a motor for cranking purposes, may be automatically connected to the engine at one ratio 30 while, when acting as a generator, it will be connected to the engine at another ratio.

Further objects and advantages of the present invention will be apparent from the following description, reference being had 35 to the accompanying drawings, wherein a preferred form of one embodiment of the present invention is clearly illustrated.

In the drawings:

40 Figure 1 is a chassis view, showing the location and relation of the dynamo-electric machine used therewith.

Fig. 2 is a view partly in section and partly in elevation of the dynamo-electric machine, showing the magnetic shifting apparatus of the connecting gears.

45 Fig. 3 is an end view of the machine shown in Fig. 2, certain parts being removed for sake of clearness.

Fig. 4 is a sectional view of the dynamo-50 electric-machine, showing the form and construction of the field magnets and relative parts.

Fig. 5 is a detail sectional view of the gear end portion of the electric machine.

Fig. 6 is an end elevation of the gears and 55 their included clutches shown in Fig. 5.

In these drawings the well known appurtenances of a motor vehicle, such as are almost universally employed, and hence well known, are not illustrated except diagrammatically, the illustration being confined to the novel features of the invention, except in Fig. 1, which shows the general arrangement of parts mounted on a chassis 2. The dynamo-electric-machine in this figure is 60 designated by 3 and its gear connection with the engine by 4.

The electric machine, when acting as a motor for cranking purposes, is adapted to be connected to the engine by means of a 70 train of reducing gearing shown in Figs. 2, 5 and 6. These gears are adapted to be brought into operation by means of a magnetic shifting element, which is brought into effect through the operation of various circuit controlling devices, which are clearly illustrated and described in the above-mentioned application.

The various gear connections are shown 80 in Figs. 5 and 6, in which 24 represents the armature shaft of the dynamo-electric-machine. This shaft carries near its end a pinion 25 and a clutching element, which comprises a disk 26 with notches of the form shown in Fig. 6. Concentric with the clutch 85 disk is a gear wheel 27. Rollers or balls 28 are retained in the notches between closing plate 29 and the inner periphery of the gear wheel 27. A projection 30 from the gear wheel 27 is connected with the timing gears 90 in the engine.

Beneath the armature shaft and parallel therewith is a shaft or spindle 31, which carries a clutching element 32, similar in construction to that described above and 95 provided with a pinion 33. A gear wheel 34 concentric with and cooperating with the clutch element, carries a yoke or grooved extension 35, and the clutch and pinion are closely mounted on the shaft 31 and slidable 100 thereon, so that in one position the pinion 33 will gear with the wheel 27 and the gear 34 with the pinion 25, but when moved to the right (see Fig. 5), it will be entirely out of such gear.

105 The movement of the clutch element 32 is effected and controlled by shifting rods 36 (see Fig. 3), the free ends of which engage

with the yoke or groove 35, while their opposite ends are secured in iron armature blocks 37, fitted to slide in receptacles formed by the pole pieces of the dynamo, and covers 5 38, as shown in Fig. 4.

In Fig. 2 the above described elements are shown in their normal position, but assuming the field magnets of the dynamo-electric-machine to be strongly energized, 10 its frame or pole pieces will tend to draw the blocks 37 toward the gear wheels. This will move the gear wheel 34 and clutch 32 to the right against the force of a spiral spring 39, and bring the gear 34 and pinion 15 25 and pinion 33 and gear 27 into mesh. These parts are returned to normal position by spring 39 as soon as the circuit in the dynamo-electric-machine is interrupted.

The result of the meshing of the gears 20 above set forth is as follows: When the circuit to the dynamo-electric-machine is closed, the latter will slowly rotate and shift the clutch to the right to establish the gearing connection described. The cranking 25 operation of the engine will thus be effected and the shaft 24 will be turned in an anti-clockwise direction. The rollers 28 of the clutch 26 traveling to the wide portion of the notches will now slip, but the clutch 32 30 will bind, and power will then be transmitted through the pinion 25, the gear wheel 34, the pinion 33, the gear wheel 27 and the projection 30 to the timing gears of the engine. As soon as the engine becomes self- 35 actuated, its speed will greatly increase, which will result in the projection 30 being driven by the engine instead of by the dynamo-electric-machine, whereupon the gear 27 will be rotated in a counter-clockwise direction, 40 which will result in locking the clutch 26 thereby causing a direct drive of the shaft 24. At the same time, the pinion 33 will be rotated by the gear 27 in a clockwise direction, whereby the rollers of clutch 32 will 45 be caused to slip, thus preventing any ill effect due to the difference in speed between the two gear wheels 27 and 34.

Upon reference to Fig. 4, will be seen in section the field coils of coarse wire, represented by large squares 61, and field coils of fine wire, represented by small squares 51. It is to be understood that when the dynamo-electric-machine is operating to start the engine, current will pass through 55 both field windings to create a strong magnetic field to produce the necessarily heavy starting torque; and when the machine is driven as a generator by the engine, current will pass only through the coils of fine wire 60 51 to produce a much weaker field. The particular means for changing from a strong to a weak magnetic field is fully disclosed in the application above referred to, and forms no part of this invention which depends 65 only on the presence of a strong motor

field, or a weak generator field, without regard to the apparatus for changing the strength of the field.

The magnetic field, in operation when the dynamo-electric-machine is used as a 70 motor, is strong enough to draw the armature blocks 37 toward pole pieces and cause the meshing of the gears as described, the attractive force of the field overcoming the spring 39, and compressing it. When the 75 machine is used as a generator, the magnetic field employed is too weak to hold the armature blocks 37 in attracted position against the compression of spring 39, hence the spring will overcome the weak magnetic 80 field and cause unmeshing of the gears. As already pointed out, this unmeshing action may take place while armature shaft 24 is directly driven through parts 30, 27, and 26.

While the form of mechanism herein shown 85 and described constitutes a preferred form of embodiment of the invention, it is to be understood that other forms might be adopted, all coming within the scope of the claims which follow. 90

What we claim is as follows:

1. In an engine starter, the combination with a dynamo-electric-machine having an armature and field magnets; of means for connecting the engine and machine including a movable member; and means for actuating said movable member including a part independent of said armature and shiftable into proximity to adjacent poles of said field magnets by magnetic attraction. 100

2. In an engine starter, the combination with a dynamo-electric-machine having an armature and field magnets; of gearing between the same and the engine, comprising fixed and axially movable gears; a rod 105 slidably mounted on the dynamo frame; a movable member connected to the rod and coöperating magnetically with the magnets of the dynamo; connections between the rod and the movable gear, whereby the gears are 110 thrown into mesh when the field magnets are energized, as set forth.

3. In an engine starter, the combination with a dynamo-electric-machine having an armature and field magnets; of gearing between the same and the engine; said machine operating with a strong magnetic field to start the engine, and operating with a weak magnetic field when driven as a generator by the engine; a movable member coöperating magnetically with the magnets in the dynamo; connections between the same and the gears, whereby the latter are thrown into mesh when the field magnets are energized; means operating when the generator field is 115 120 in operation to throw the gears out of mesh; and independent means acting automatically to connect the machine to the engine when driven as a generator. 125

4. In an engine starter the combination 130

- with a dynamo-electric-machine having an armature and field magnets; of gearing between the same and the engine; said machine operating with a strong magnetic field to 5 start the engine, and operating with a weaker magnetic field when driven as a generator by the engine; means independent of the armature of the machine and coöperating with the field magnets to be actuated 10 by the stronger magnetic field to throw the gears into mesh; means capable of operation against the weaker magnetic field to throw the gears out of mesh; and independent means to transmit motion from the engine 15 to the machine, when running as a generator.
5. In an engine starter, the combination with a dynamo-electric-machine having an armature and field magnets; of gearing between the same and the engine; said machine 20 operating with a strong magnetic field to start the engine, and operating with a weaker magnetic field when driven as a generator by the engine; means independent of the armature of the machine and coöperating 25 with the field magnets to be actuated by the stronger magnetic field to throw the gears into mesh; a spring capable of operation against the weaker magnetic field to throw the gears out of mesh; and independent 30 means to transmit motion from the engine to the machine when running as a generator.
6. In an engine starter, the combination with a dynamo-electric-machine having an armature and field magnets; of a direct 35 drive and speed reduction gearing between the same and the engine; said machine operating with a strong magnetic field to drive the engine through the reduction gearing, the direct drive not being operative, 40 said machine operating with a weaker magnetic field when being driven as a generator through the direct drive, the reduction gearing not being operative; means independent of the armature of the machine and coöperating 45 with the field magnets to be actuated by the stronger magnetic field to move the re-

duction gearing into operation; and means operative against the weaker magnetic field to move the reduction gearing out of operation.

50

7. In an engine starter, the combination with an engine; of a dynamo-electric-machine having an armature and field magnets, including a plurality of pole pieces, adjacent pole pieces being formed so as to coöperate together to provide a recess at the side of the machine; of gearing between the machine and the engine including axially movable gears; a rod slidably mounted on the dynamo frame; a block connected to the rod and 60 adapted to move into the recess when attracted by the magnets of the dynamo; and connections between the rod and the movable gear whereby the gears are thrown into mesh when the field magnets are energized.

65

8. In an engine starter, the combination with a dynamo-electric-machine having an armature and field magnets; of means for connecting the engine and machine including a shiftable gear; and means for actuating said gear including a part independent of said armature and shiftable into proximity to adjacent poles of said field magnets by magnetic attraction.

70

9. In an engine starter, the combination with a dynamo-electric-machine having an armature and field magnets; of means for connecting the engine and machine including an axially movable gear; and means for actuating said gear including a part independent of said armature and slidably axially of said machine into proximity to adjacent poles of said field magnets by magnetic attraction.
